UNITED STATES PATENT OFFICE.

CHARLES M. KUHN, OF KEARNEY, NEBRASKA, ASSIGNOR OF ONE-THIRD TO ADAM M. KUHN AND JACOB E. HERMAN, BOTH OF KEARNEY, NEBRASKA.

RABBETTING APPARATUS.

1,115,687.

Specification of Letters Patent.

Patented Nov. 3, 1914.

Application filed June 5, 1914. Serial No. 843,273.

To all whom it may concern:

Be it known that I, CHARLES M. KUHN, a citizen of the United States, residing at Kearney, in the county of Buffalo and State 5 of Nebraska, have invented a new and useful Babbetting Apparatus, of which the following is a specification.

The present invention appertains to a babbetting apparatus and aims to provide a 10 novel and improved appliance for rebab- betting or relining the pitmen or connecting rods of internal explosion engines, al- though the device may be employed for re- babbetting the bearings or other parts as 15 well.

One of the specific objects of the present invention is to provide a novel means for effectively holding the pitman or connecting rod in true or proper position while being 20 babbitted or relined.

Another object of the present invention is to provide unique means for molding the liner of Babbitt metal within the bearing of the pitman or connecting rod.

25 A further object of the present invention is to provide a novel means for trimming the interior and ends of the Babbitt metal liner.

It is also within the scope of the present 30 invention to provide a babbetting apparatus which will be of improved construction throughout, to enhance the utility thereof, and whereby a pitman or connecting rod may be readily and properly rebabbitted or 35 relined by inexperienced persons, as well as skilled mechanics.

With the foregoing and other objects in 40 view which will appear as the description proceeds, the invention resides in the combi- nation and arrangement of parts and in the 45 details of construction hereinafter described and claimed, it being understood that changes in the precise embodiment of the invention herein disclosed can be made with- 50 in the scope of what is claimed without de- parting from the spirit of the invention.

The invention has been illustrated in its 55 preferred embodiment in the accompanying drawing, wherein:

Figure 1 is a plan view of the apparatus, 60 portions being shown in section, and the centering cone being applied to the bearing of the pitman or connecting rod. Fig. 2 is 65 a longitudinal section of the apparatus, portions being broken away, illustrating the

mold elements applied to the bearing of the pitman or connecting rod. Fig. 3 is a trans- 70 verse section of the apparatus, illustrating the cutter in position for boring or trimming out the Babbitt metal liner. Fig. 4 is an 75 enlarged sectional detail illustrating the cutter for trimming the ends of the Babbitt metal liner. Fig. 5 is an enlarged elevation 80 of the cutting device illustrated in Fig. 4. Fig. 6 is a transverse sectional detail illus- 85 trating the device in condition for casting 90 the Babbitt metal.

The frame of the present invention em- 95 bodies a base or body 1 having attached thereon a pair of end brackets or standards 2 and 3 having the respective bearings or sleeves 4 and 5 at their upper ends.

A tubular adjusting screw 6 is threaded 100 through the bearing or sleeve 4, and is equipped at its outer end with a suitable 105 hand wheel 7 for conveniencing the rotation thereof.

A shaft or spindle 8 is journaled and slid- 110 able through the tubular adjusting screw 6, and through the bearing or sleeve 5, the ad- 115 justing screw 6 serving as a bearing for the shaft or spindle also. That end of the shaft or spindle 8 which protrudes beyond the hand wheel 7 of the adjusting screw, has 120 keyed or secured thereon, a hand wheel 9 125 provided with a crank handle 10, whereby 130 the hand wheel 9 may be readily turned by hand to rotate the shaft or spindle 8. The 135 shaft or spindle 8 is adapted to be with- 140 drawn from the bearing 5, by sliding the 145 shaft or spindle through the tubular screw 6, the hand wheel 9 being moved away from 150 the hand wheel 7. In order to hold the shaft 155 or spindle 8 against longitudinal movement 160 relative to the screw 6 to thereby cause the 165 shaft 8 to be slid longitudinally when the 170 screw 6 is rotated, a screw 11 is carried by 175 the hub of the hand wheel 7 and engages 180 an annular groove 12 provided upon the 185 shaft 8. Thus, when the screw 11 is en- 190 gaged into the groove 12, the shaft is caused 195 to move longitudinally with the adjusting 200 screw, but the shaft may rotate readily within the screw for the purposes which will 205 hereinafter appear.

The frame of the machine or apparatus 210 further includes a transverse bracket dis- 215 posed at or projecting to one side, and hav- 220 ing its inner end attached to the base 1 be- 225 tween the brackets or standards 2 and 3, but 230

adjacent the standard 3. A side bracket 13 is provided with an elongated slot 14, in which is slidably and removably disposed a clamping bolt 15.

- 5 A pitman or connecting rod clamp 16 is carried by the inner end of the bracket 13, beyond the inner end of the slot 14, and this clamp 16 embodies an upright clamping bar 17 coöperating with the inner end of the bracket 13 to provide means for receiving the body of a pitman or connecting rod. Bolts 18 are engaged through the ends of the clamping bar 17 and the inner end portion of the bracket 13 and a jam screw 19 is 10 threadedly engaged through the bracket 13 between the draft or clamping bolts 18 and coöperates with the intermediate portion of the clamping bar 17 to clamp or bind the pitman or connecting rod therebetween.
- 15 Various devices are applicable to the shaft 8, for coöperation with the bearing of the pitman or connecting rod which is applied to the bracket or holder 13. Thus, the centering cone 20 having a longitudinal bore or 20 opening is adapted to be slid onto the shaft 8 as will hereinafter appear.

A molding device is also applicable to the shaft 8, and embodies a pair of collars 21 having flanges or heads 22 at their adjacent 25 ends and adapted to rest against or coöperate with the sides or faces of the pitman or connecting rod bearing. The faces of the flanges or heads 22 are provided with angular grooves 23 for forming the beads or 30 flanges at the ends of the Babbitt metal liner as will hereinafter appear. Each of the collars 21 also carries a screw 24 for clamping it in place upon the shaft 8, and one of the flanges or heads 22 is provided with a gate 35 25 for permitting the molten Babbitt metal to be poured into the molding device, as will hereinafter appear.

The shaft 8 is provided at the proper point, with a diametrical opening 26 therethrough in which a cutter 27 is disposable, a set screw 28 being carried by the shaft 8 to bind the cutter 27 in any adjusted position to which it is set within the opening or socket 26.

- 50 A cutting or trimming device is applicable to each of the flanges or heads 22 of the collars 21 and embodies an approximately U-shaped member 29 adapted to straddle one or the other of the flanges or heads 22, one 55 arm of the member 29 having a set screw 30 for binding the said member in place upon the corresponding flange or head 22. The other arm of the member 29, which is adapted to be disposed against the face of the flange or head 22, is provided with a longitudinal slot 31 in which is fitted a cutting blade 32. A set screw 33 is carried by that arm of the member 29 which has the slot 31, to bind or clamp the cutting blade 32 within 60 the said slot. The cutting blade 32 pro-

jects from the corresponding arm of the member 29, and its free or outer edge is provided with a recess or reentrant portion 34 which is in the form of the bead or flange at the end of a Babbitt metal liner.

In order that the use of the present apparatus may be better understood, an ordinary pitman or connecting rod 35 has been illustrated in the drawing, the same having the bearing 36 at one end to engage the usual crank shaft, and the bearing 37 at its other end for embracing the wrist pin of the piston. Supposing it is desired to rebabbitt or reline the bearing 36 of the pitman or connecting rod 35, then the cap of the bearing 36 is first removed, and the old liner taken out. The cap of the bearing 36 is then replaced, and a pair of division plates 38 of suitable size and proportions are clamped under the cap of the bearing 36, to divide the liner when it is molded within the bearing, it being understood that the liners are ordinarily divided in halves.

The next step is to apply the pitman or connecting rod 35 to the bracket or holder 13. To accomplish this, the pitman or connecting rod 35 is placed between the clamping plate 17 and the screw 19, which may be readily accomplished, and the clamping bolt 15 which has been previously removed, and inserted through the wrist pin bearing 37 of the pitman or connecting rod and through the slot 14. The shaft 8 is then withdrawn from the bearing 5, to permit the bearing 36 of the pitman or connecting rod to be adjusted or set approximately coaxial with the shaft, and when the shaft 8 has been retracted through the tubular screws 6, the centering cone 20 is slid onto the inner end of the shaft and the shaft is again brought to normal position, as seen in Fig. 1. Then, the centering cone 20 may have its apical portion or smallest end inserted into the bearing 36 of the pitman or connecting rod to center the said bearing with respect to the shaft 8. When the bearing 36 is properly centered, the bolt 15 is tightened, to clamp the outer end of the pitman or connecting rod, and the bolts 18 and jam screw 19 are then tightened to clamp the central or body portion of pitman or connecting rod. In this manner, the pitman or connecting rod is held firmly in true position in order that the bearing 36 will be held in coaxial relation with respect to the shaft 8. The shaft 8 is then again retracted from the bearing 5 and the pitman or connecting rod bearing 36, so that the centering cone 20 may be slipped off of the shaft.

The molding device is then assembled 125 with the shaft 8 and the bearing 36, the collars 21 being applied on the shaft 8 at the opposite sides of the bearing 36 when the shaft 8 is slid back to normal position, as seen in Fig. 2. The flanges or plates 22 are 130

then slid against or adjacent the opposite sides of the bearing 36, and are clamped in place by tightening the set screws 24. It is also desirable to place a tubular or hollow core 39 upon the shaft 8 between the flanges or plates 23 to increase the bore of the liner when it is cast. The molten Babbitt metal is then poured through the gate 25 to fill the mold formed by the flanges or plates 22 in connection with the walls of the bearing 36. When the metal hardens or sets, it will form the rough liner 40 and the grooves 23 of the flanges or heads 22 will form the beads or flanges 41 at the ends of the liner 40. The collars 21 are then loosened, by loosening the set screw 24, and the said collars are then either slid away from the bearing 36, or removed from the shaft 8, to expose the liner 40. The sleeve or tubular core 39 is also slid out of the liner 40. The liner 40 is then reamed out, by applying the cutter 27 within the opening 26 of the shaft 8, and clamping the cutter in projected position by tightening the set screw 28. The screw or key 11 of the adjusting screw 6 is then engaged to the annular groove 12 of the shaft 8, whereby the shaft will be caused to move longitudinally with the adjusting screw. The shaft is then rotated through the medium of the crank wheel 9, and the screw 6 is threaded inwardly slowly, to feed the shaft 8 longitudinally, and whereby the cutter 27 will bore out the liner 40 to the proper internal diameter. The cutter 27 is then withdrawn, or pushed back completely within the opening 26 of the shaft, so as to be out of the way. The final step in completing the liner is to trim the ends or beads 41 thereof. This is accomplished by placing the member 29 astride one of the flanges or plates 22, so that the cutting blade 32 will properly coöperate or engage the corresponding bead or flange 41 of the liner 40. The shaft 8 is then rotated, and is fed longitudinally properly through the medium of the adjusting screw 6, in order that the recess 34 of the cutting blade 32 will properly trim the corresponding bead or flange 41 of the liner. The member 29 is then removed and applied to the other flange or plate 22, to trim the bead or flange at the other end of the liner. It is to be understood, that when the member 29 is applied to one of the flanges or plates 22, the corresponding collar 21 is clamped in place upon the shaft 8, whereby the trimming blade 32 will be properly moved longitudinally with the shaft, as well as being rotated to trim off the end or bead of the liner. The liner is then completed, and the pitman or connecting rod may be removed by first retracting the shaft 8 and removing the collars 21, and then releasing the pitman or connecting rod from the clamp 16 and clamping bolt 15. When it is desired to form a number of

similar liners, the pitman or connecting rod may be repeatedly employed while held by the bracket or holder 13, the completed liner being removed each time by detaching the cap of the bearing 36, in which event a new or successive liner may be formed in the manner above described. After the liner is completed, the dividing plates 38 are removed by removing the cap of the bearing 36, and the bearing 36 will then be in condition for use to be applied to the crank shaft. 75

The present apparatus is adapted for re-babbitting or relining bearings of various pitmen or connecting rods, and provides means whereby an inexperienced person, as well as a skilled mechanic may readily re-babbit or reline the pitman or connecting rod bearings. The other advantages and capabilities of the present apparatus will be obvious to those familiar in the art, and further comment is deemed unnecessary. 85

Having thus described the invention, what is claimed as new is:—

1. In an apparatus of the character described, a pair of bearings, a tubular adjusting screw threaded through one bearing, a shaft journaled through the said screw and the other bearing and adapted to be retracted from the last mentioned bearing, the adjusting screw and shaft having interengagable portions to hold the shaft against longitudinal movement relative to the screw, and a clamp disposed between the said bearings and adapted to hold a connecting rod with one of its bearings coaxial with the shaft. 90

2. In an apparatus of the character described, a pair of bearings, a shaft journaled therethrough and adapted to be retracted from one of the said bearings, and a connecting rod holder disposed intermediate the said bearings and including a bracket having a slot, a clamping bolt engaged in the said slot and adapted to engage one bearing of a connecting rod, and an adjustable clamp carried by one end of the bracket to clamp the body of the connecting rod to hold the other bearing thereof coaxial with the shaft. 105

3. In an apparatus of the character described, a pair of bearings, a shaft journaled therethrough and retractable from one bearing, and a connecting rod holder disposed between the said bearings and including a bracket, an adjustable clamping bolt carried thereby and adapted to engage one bearing of a connecting rod, a clamping bar, bolts connecting the ends of the clamping bar and said bracket, and a jam screw threadedly engaging through the bracket and coöperating with the central portion of the said bar 110 to clamp the body of a connecting rod. 120

4. In an apparatus of the character described, a pair of bearings, a shaft journaled therethrough and retractable from one bearing, a clamp disposed between the said bear- 130

ings and adapted to hold a connecting rod with one bearing coaxial with the shaft, and a pair of plates applicable to the shaft, said plates being adapted to coöperate with the 5 sides of the said bearing and having means for clamping them in place upon the shaft. In testimony that I claim the foregoing

as my own, I have hereto affixed my signature in the presence of two witnesses.

CHARLES M. KUHN.
